DESIGN.

A. LOWY.

CORNER IRON.

APPLICATION FILED JUNE 20, 1916.

49,615.

Patented Sept. 5, 1916.

Adolph Lowy Inventor
By his Attorney
Isaac B. Stevens.

UNITED STATES PATENT OFFICE.

ADOLPH LOWY, OF NEW YORK, N. Y.

DESIGN FOR A CORNER-IRON.

49,615.

Specification for Design.

Patented Sept. 5, 1916.

Application filed June 20, 1916. Serial No. 104,819. Term of patent 3½ years.

To all whom it may concern:

Be it known that I, ADOLPH LOWY, a citizen of the United States, and a resident of the borough of Bronx, county of Bronx, city and State of New York, have invented a new, original, and ornamental Design for a Corner-Iron, of which the following is a specification, reference being had to the accompanying drawing, forming part thereof.

The figure is a perspective view of a corner iron, showing my new design.

I claim:

The ornamental design for a corner-iron, as shown.

ADOLPH LOWY.

Witnesses:

PATRICK A. BOLGER,
ETHEL S. HUGHES.
